UNITED STATES PATENT OFFICE.

HERBERT H. STEELE, OF MARCELLUS, NEW YORK, ASSIGNOR TO THE MONARCH TYPE-WRITER COMPANY, OF SYRACUSE, NEW YORK, A CORPORATION OF NEW YORK.

TYPE-WRITING MACHINE.

No. 914,081.

Specification of Letters Patent.

Patented March 2, 1909.

Application filed December 30, 1908. Serial No. 470,032.

To all whom it may concern:

Be it known that I, HERBERT H. STEELE, citizen of the United States, and resident of Marcellus, in the county of Onondaga and State of New York, have invented certain new and useful Improvements in Type-Writing Machines, of which the following is a specification.

My invention relates to carriage feeding devices for typewriting machines and its object is to provide improved devices of the class specified.

To the above and other ends the invention consists in the features of construction, combinations of devices and arrangements of parts hereinafter described and particularly pointed out in the claims.

I have shown my invention as applied to a Monarch typewriting machine but the nature of the invention is such that it may be adapted to other styles of writing machines.

When an "ordinary feed" escapement, that is, an escapement which permits the carriage to advance a letter space during the return stroke of a printing key, is employed, it has been common heretofore to make use of a back stop like that shown in the patent to Gabrielson No. 717,837 granted January 6th, 1903. In some styles of Monarch machines and in other machines, when the final margin stop has arrested the carriage it is sometimes desirable to add one more character to complete the word or to print a hyphen to properly divide syllables of an unfinished word. In such case the operation of the usual margin release key disengages the final margin stop and carriage stop and so releases the escapement rocker, permitting one more character to be printed; but there is no corresponding feeding movement of the carriage at this time because of the fact that another stop on the carriage (the tabulator stop in the present case) has previously contacted with a stop fixed on the frame of the machine. The result is that the depression of the character key for the last character rocks the dog rocker forward and allows the stepping dog to be pressed by its spring past the tooth of the escapement wheel with which said stepping dog had previously been engaged; but the carriage being at this time prevented from moving, there is nothing to overcome the

dog spring and restore the dog to normal position when the rocker rocks backward. 55 Under these conditions, when the carriage is restored from left to right and has been arrested it will move forward two spaces instead of one only as is common with the form of back stop referred to. If the operator fails to thereafter move the carriage back one space an irregular left-hand margin will result. The same trouble may occur if the line lock sticks or for some other reason fails to operate properly on the dog 60 rocker when the final arrest of the carriage takes place. To remedy this defect I substitute for the usual back stop an improved back stop which is mounted on the dog 65 rocker independently of the escapement 70 dogs. In order to prevent the substituted back stop from interfering with the proper operation of the escapement dogs, said back stop is mounted in a novel way on the dog rocker so that the dog rocker may move at 75 times relatively to the back stop.

In the accompanying drawings, which illustrate one form of my invention, Figure 1 is a vertical sectional view taken transversely of the carriage and showing the carriage feeding or escapement devices. Fig. 2 is a rear elevation partly in section of the escapement devices in their mounting. Fig. 3 is a rear elevation showing certain of the escapement devices, the escapement wheel 80 being shown in dotted lines and a section of part of the dog rocker also being shown. Fig. 4 is a view corresponding to Fig. 3 but illustrating a known form of back stop heretofore employed. Fig. 5 is a front elevation 85 of the carriage with the platen removed, the escapement devices being omitted and the line locking devices being shown. Fig. 6 is a view corresponding with Fig. 5 but omitting some of the parts shown in Fig. 5 and illustrating other parts in different relations from those in which they appear in said Fig. 5. Fig. 7 is a vertical sectional view illustrating part of the margin stop releasing mechanism.

The frame of the machine comprises a top 100 plate 1 from which rise standards 2 supporting fixed upper and lower grooved guide rails 3. The guide rails receive anti-friction balls or rolls 4 which also coöperate with grooves in the upper and lower faces of a slide bar 5. Said slide bar is comprised in the platen car-

rier or carriage which also includes end bars 6 extending forward from the slide bar and providing bearings for a rotary platen 7. Arms 8 which are pivoted on the end bars 5 and extend rearward have a feed rack 9 secured to their rear ends. The rack 9 normally meshes with a feed pinion 10 which is fixed to the forward end of a shaft 11 bearing in a bracket 12 secured to the top plate. 10 Suitably secured to the rear end of the shaft is a housing 13 on which is pivoted a spring-pressed pawl 14 (Fig. 2), said pawl coöperating with a ratchet wheel 15 which is loosely mounted on the shaft 11 and is suitably fixed 15 to a circular rack or escapement wheel 16 also loose on the shaft 11, said escapement wheel or rack having teeth 17, the working face of each tooth being straight and the opposite face curved. Coöperative with the 20 teeth of the escapement wheel are escapement dogs 18 and 19 mounted at the top of a vertically disposed arm 20 of a dog carrier or rocker which also comprises a shaft-like portion 21 and a horizontally disposed arm 22. 25 The forward dog 18 is what is commonly termed a stepping dog or feed dog, and is movable on the dog carrier or rocker, being arranged in a slot formed in a lateral lug 20^a on the vertical arm of the rocker and pivoted 30 on a screw 23 which is secured horizontally in said lug. A coiled spring 24 (Fig. 2) is arranged between the side of the dog rocker and the adjacent face of the stepping dog, said spring tending constantly to turn said 35 dog on its pivot 23 away from the face of the dog rocker. Normally, however, the dog is maintained in contact with the face of the dog rocker by reason of the engagement of one of the teeth of the escapement wheel 40 with said dog. The rear dog 19 is normally disengaged from the escapement wheel and is what is commonly termed a holding dog being rigidly secured to the dog rocker as by a screw 25. The ends of the shaft-like portion 45 21 of the dog rocker are depressed to receive the points of adjustable screw pivots 26 which are supported on a plate or bracket 27 depending from the under side of the top plate. The dog rocker spring (not shown) 50 normally maintains an adjustable limiting stop 28 in engagement with the bottom edge of the bracket 27. An adjustable limiting stop 29 on the vertically disposed arm of the dog rocker is adapted to contact with the 55 rear face of the bracket 27 to limit the forward rocking movements of said dog rocker. A link 30 is pivotally connected at its upper end to the horizontal arm 22 of the dog rocker and is part of a train of actuating devices 60 (not shown) by which the dog rocker is operated from the printing keys. When a printing key or the space bar is depressed the link 30 is pulled down, rocking the dog rocker and moving the stepping dog 18 forward out

of the escapement wheel and bringing the 65 holding dog 19 into engagement with the working face of that tooth 17 from which the stepping dog has just separated. As soon as the stepping dog disengages from the escapement wheel it will be swung away from the 70 dog rocker by its spring 24 until arrested by its own extension or tail contacting with the side of the rocker. On the return movement of the dog rocker the holding dog 19 moves backward out of the escapement wheel and 75 the stepping dog 18 is brought into the path of said wheel behind the previously engaged tooth, whereupon the carriage will be moved forward a letter space under the pull of the usual spring drum (not shown).

A toothed stop bar 31 (Figs. 5-7) is pivoted at its ends on screw pivots 32 supported on lugs 33 rising from the upper fixed carriage rail 3. Adjustably mounted on the stop bar 31 at the left-hand side are stop members 85 34 and 35. The stop member at the right-hand side of the machine is not shown. The member 34 carries a bell trip 36 and a stop proper 37 for the right-hand margin. The member 35 carries a stop proper 38, 90 usually termed the final margin stop. As shown in Fig. 5 the member 35 is at the limit of its leftward movement along the stop bar 31, being in contact with a pin 31^a fixed to and rising from the stop bar; while 95 the stop member 34 is arranged at a plurality of letter space distances to the right of the member 35. Coöperating with the bell trip 36 and the stops proper 37 and 38 is a carriage stop 39 which is at the top of and integral with the upright arm of a bell-crank lever 40 pivoted at 41 to the slide bar 5 and normally maintained by a spring 42 against a stop 43. The horizontal arm or bell-crank lever 40 carries a roller 44 which contacts 100 with the upper edge of a bail 45, said bail extending longitudinally of the lower rail 3 at the front thereof, being provided with rearwardly bent end portions which receive pivot screws 46 supported in the ends of the 105 lower rail 3. A leaf spring 47 normally maintains the bail 45 in the position shown in Fig. 5. The bail carries a pin 48 which coöperates with the tail 49 of a gravity locking hook 50 pivoted at 51 to the lower rail 3. 110 The hook 50 is normally maintained by the bail 45 in inoperative position as shown in Fig. 5 but when the bail is depressed the hook will gravitate towards the right to engage with an adjustable finger 52 on the link 30 to prevent the lowering of said link and rock the escapement devices out of operation.

During movements of the carriage in printing direction, the carriage stop 39 will 125 first engage with the bell trip 36 and will be swung on its pivot by said bell trip, causing, when released, the bell to be rung in the

usual way by the hammer (not shown.) Thereafter said carriage stop will engage with the margin stop 37 and will be turned on its pivot until it engages with a back stop 5 53 on the slide bar. During this turning movement the roller 44 will depress the bail 45 against its spring and finally will permit the gravity locking hook 50 to engage with the finger 52, thus locking the escapement at 10 the same time that the carriage is arrested because of the contact of the bell crank lever 40 with the stop 53. In order to release the carriage for further printing, the usual margin release key (not shown) may be operated 15 to actuate the releasing devices, said releasing devices including a link 54 (Fig. 7) having a pin and slot connection with the stop bar 31. When the margin release key is actuated the link 54 will be pulled down, rocking 20 the stop bar 31 on its pivots and lifting the stops at the front side of said bar, thus causing the stop 37 to be lifted from and to release the carriage stop 39, permitting the devices for locking the escapement to be restored to 25 normal position by their springs. Thereafter additional characters may be written until the advance of the carriage brings the stop 39 into contact with the final margin stop 38 and causes the bell crank 40 to be 30 rocked on its pivot to the position shown in Fig. 6, with the result that the locking hook 50 will again be brought into operation to lock the escapement. At this time a stop 35 55, which is in the form of a lug projecting rearwardly from the slide bar 5, and which is one of the regular tabulator stops; will have been brought into contact with a stop 56 which is in the form of a screw adjustably mounted in the left-hand standard 2. Neither 40 of the stops 55 and 56 is movable out of the path of the other so that when said stops engage, no further movement of the carriage towards the left is possible. By operating the margin release key at this time, however, 45 the stop bar 31 may be rocked to disengage the final margin stop 38 from the carriage stop 39, permitting the carriage stop to return to normal position and causing the line locking hook 50 to release the link 30. The result is that thereafter on the depression of a 50 character key to print the final character, the dog rocker will be swung forward, releasing the stepping dog 18 and bringing the holding dog into engagement with the escapement wheel; but on releasing the actuated character key, although the stepping dog will reenter the plane of the escapement wheel behind the tooth last engaged by said stepping dog, there will, nevertheless, be no 55 movement of the carriage, since the latter has already reached the final limit of its movement.

If the stepping dog 18 were provided with an integral back stop of the usual construc-

tion, such as that indicated at *a* (Fig. 4); the 65 relation of the stepping dog and back stop *a* with the escapement wheel at this time would be that indicated at Fig. 4, so that if the carriage were now restored from left to right until arrested and pressure thereon removed, it would advance two letter space 70 distances instead of only one letter space distance as it does ordinarily when restored from left to right and the pressure of the operator's hand removed. Unless this different point of starting be corrected before the writing of lines is begun an irregular left-hand margin would result. It will further be understood that when the stepping dog and back stop are made integral as 75 shown in Fig. 4 the manufacture is somewhat complicated and expensive, it being necessary to mill the stops to the required shape in rod or bar form and then to saw the bar into pieces of the desired thickness after 80 which two milling operations are required to complete the blank.

To obviate the defect in operation above pointed out and to lessen the cost of manufacture, I dispense with the back stop *a* and provide in lieu thereof a back stop member of the character now to be described. Said stop member comprises a hub portion 57 pivoted on a screw 58 which is threaded into the right-hand side of the dog rocker arm 20. 90 Rising from the hub 57 is an arm 59 terminating at its top in a rearwardly extending locking finger or stop portion 59^a which normally engages in one of a series of cut-outs or notches 17^a formed between the teeth 17 of the escapement wheel. The arm 59 is contiguous to the face of the dog rocker arm 20 and normally engages with the same face of the operative escapement wheel tooth 17 with which the stepping dog 18 normally 95 engages, the stop 59^a engaging with said face at a point above the dog 18 but in the same fore and aft plane therewith. A wire spring 100 60 is coiled around the hub 57 and, having one end secured in the hub 57 and the other end in the rocker, tends constantly to turn the arm 59 rearward on its pivot 58. Said arm is normally arrested by the front face of the lug 20^a which serves as a stop for the arm engaging with a contact face 59^b thereon and prevents said arm from contacting with the front face of the stepping dog 18, in which 105 case it might interfere with the proper operation of said dog.

In ordinary operation with my improvements in use, when the dog rocker is rocked forward the stepping dog 18 will swing away from the dog rocker so that on the return movement of said rocker said stepping dog will engage with the next succeeding tooth. 110 If the stop 59^a were rigid on the dog rocker 115 it might happen at times that during return movements of the rocker said stop would

contact with the front face of the advancing tooth 17 so as to prevent the stepping dog from entering the plane or path of the escapement wheel until the stop 59^a entered 5 the cut-out 17^a behind the advancing tooth. It might happen in such case that the stepping dog would not enter the plane of the wheel in time to prevent more than one tooth of the escapement wheel from escapement, 10 and that two or more teeth might escape. My improved construction renders such defective operation impossible, for if during the backward swing of the dog rocker, the rear end or face of the stop 59^a should strike the front 15 face of the advancing tooth 17, the rearward movement of the dog rocker would not be checked; nor would the stepping dog be prevented from entering the path of the advancing tooth 17. The only result would 20 be that the stop 59^a would be momentarily held from moving rearward and the spring 60 would be flexed to permit uninterrupted movement of the dog rocker rearward. In such case when the advancing tooth 17 had 25 passed the stop 59^a the latter would be pressed into the following cut-out 17^a by the spring 60.

When a stop of my improved construction is employed and the carriage stop 39 and the 30 final margin stop 38 are brought into the relation shown in Fig. 6, at which time the stop 55 on the carriage engages the stop 56 on the frame, then the carriage will be finally arrested and the escapement devices will be 35 locked. Actuating the margin stop key will release the escapement devices so that an additional character may be printed and the dog rocker vibrated. During the forward movement of the dog rocker the stepping dog 40 will step one space, as illustrated in Fig. 3, so that on the return movement of the dog rocker said stepping dog will pass behind the tooth 17 with which it had previously engaged. Said tooth, however, will not have 45 changed its position owing to the non-movement of the carriage, so that the stop 59^a will enter the same cut-out 17^a with which it had engaged prior to the vibration just referred to of the dog rocker. The relation of 50 the escapement wheel with the dog 18 and the stop 59^a at this stage is illustrated in Fig. 3. If now the carriage be restored from left to right until arrested and the operator then removes pressure from said carriage, the latter 55 will not move at all from its position of arrest. Furthermore under ordinary conditions as well as under those just considered there will be no forward movement of the carriage after its restoration from left to 60 right and arrest. Consequently the margin at the left-hand side of the written page will be uniform.

The construction provided by me is less expensive than that which it replaces; and

operates, as has been seen to overcome defects to which older constructions are subject. 65

I am aware that back stops mounted on the dog rocker are not new and therefore I do not claim the same broadly but only in the 70 combinations and with the limitations set forth in the appended claims.

Various changes may be made without departing from the spirit and scope of my invention. 75

What I claim as new and desire to secure by Letters Patent, is:—

1. In a typewriting machine, the combination of a carriage, carriage feeding devices, devices including stops for locking said carriage and said carriage feeding devices from movement, means for releasing certain of said stops to unlock said carriage feeding devices without unlocking the carriage, and a back stop coöoperative with certain of said 80 carriage feeding devices to always prevent stepping forward of the carriage after said carriage has been returned and arrested at the right-hand margin position. 85

2. In a typewriting machine, the combination of a carriage, carriage feeding devices, devices including stops for locking said carriage and said carriage feeding devices from movement, means for releasing certain of said stops to unlock said carriage feeding devices without unlocking the carriage, and a back stop coöoperative with certain of said 90 carriage feeding devices to arrest the carriage when it is returned, after the subsequent actuation of a printing key, at the same starting point at which said back stop ordinarily 95 operates to arrest said carriage. 100

3. In a typewriting machine, the combination of a carriage, carriage escapement devices including a toothed escapement wheel, 105 devices including stops for locking said carriage and said escapement devices from movement, means for releasing certain of said stops to unlock the escapement devices without unlocking the carriage, and a back 110 stop coöoperative with said toothed escapement wheel to arrest the carriage when it is returned, after the subsequent actuation of a printing key, at the same starting point at which said back stop ordinarily 115 operates to arrest said carriage. 120

4. In a typewriting machine, the combination of a carriage; carriage escapement devices including a toothed escapement wheel, coöoperating feed dogs and a dog rocker carrying said feed dog devices; means including stops for locking said carriage and said escapement devices from movement; means for releasing certain of said stops to unlock the escapement devices without unlocking 125 the carriage; a back stop pivoted on said dog rocker; a spring coöoperative with said back stop; and a limiting stop on said dog

rocker for said back stop, said back stop co-operating with said toothed escapement wheel to always prevent stepping forward of the carriage after said carriage has been returned and arrested at the right-hand margin position.

Signed at Syracuse, in the county of Onon-

daga and State of New York this 26th day of December A. D. 1908.
